METHOD OF MAKING SLIDERS

Filed June 29, 1928

UNITED STATES PATENT OFFICE

GEORGE E. PRENTICE, OF BERLIN, CONNECTICUT

METHOD OF MAKING SLIDERS

Application filed June 29, 1928. Serial No. 289,288.

This invention pertains to separable fasteners of that type of which a good example is disclosed in the patent to Prentice and Legat, No. 1,658,392 dated February 7, 1928 and relates more particularly to a process or method of making an improved slider.

The usual form of slider employed in such fasteners comprises spaced substantially parallel front and rear wings or plates united at or near one end by a relatively narrow connecting portion or neck, the inner opposed surfaces of the wings having cam-like members which, in cooperation with certain elements associated with the connecting member or neck, define guides for the opposed series of fastener elements. The successful operation of such a slider is dependent upon the maintenance of the wings in accurately spaced relationship, but as the wings are united at or near one end only and as the slider is subjected to severe stresses tending to spread the wings apart, difficulty has been experienced in making a slider sufficiently rigid without making it unduly heavy and cumbersome.

Various modes of making such sliders have heretofore been proposed. For example, attempts have been made to produce them by drop forging or die casting, but such methods are expensive and from the nature of the operation, the resultant sliders are heavy, cumbersome, rough, and generally unsatisfactory. A more common and fairly successful method consists in making the slider of sheet metal by punching and bending operations, but since sheet metal bends so easily, it is usually necessary to reinforce a sheet metal slider by means of rivets, external yoke pieces, ribs or the like, requiring several successive operations in the manufacture of such a slider, thereby increasing the cost of production, while the finished slider often presents a clumsy, angular, and unpleasing appearance. In one proposed modification of the sheet metal slider, the metal at the neck of the blank is swaged to provide a heavy projecting rib, and when the blank is bent this rib, which is disposed at the inner side of the bend, provides extra thickness designed to give greater stiffness at

this point. However, in bending the blank, this heavy rib merely folds upon itself, leaving a crack or fissure between its contacting faces, and as the fibers of the thick metal are heavily stressed and distorted in bending, this arrangement in reality affords little, if any, more resistance to separation of the wings than does the ordinary unreinforced sheet metal slider. Moreover, in such construction, even more than in other usual types of slider, the inner surface of the neck is irregular, rough and varies in configuration in different sliders, and as this inner surface of the neck acts like a cam in performing the important function of guiding the opposed series of fastener elements as they approach and recede, the slider so constructed often fails to work with the desired ease and smoothness.

In accordance with the present invention I provide a slider possessing the inherent stiffness and strength which results from integral homogeneous construction and which works with the greatest ease and smoothness, but which is markedly different from other integral constructions produced by die casting or the like operations in that it is light in weight, of small dimensions and of pleasing appearance. The new slider also represents a distinct advance over usual sheet metal constructions in its neatness, freedom from external stiffener yokes or ribs, low cost of production and small size. This slider may be used with fasteners of the kind in which each series of fastener elements consists of independent members attached to a flexible stringer, as illustrated for example in my aforesaid patent,—or of the general type described in my Patent No. 1,562,253, November 17, 1925 in which the fastener elements of each series form portions of a continuous length of wire.

In accordance with this invention I produce the slider from a solid metal blank of proper dimensions by a mechanical process or method in which the principal parts of the slider body result solely from cutting so that the normal fibrous structure of the metal is not disturbed or unduly stressed, and although certain minor features require bend-

ing or similar operations, no substantial weakening of the slider body results therefrom. All of the various steps in the production of the slider body are readily performed by proper mechanisms at high speed and with low labor cost, resulting in a product of accurately uniform and finished character capable of performing its intended function with the highest ease and efficiency, and 10 exhibiting surprising strength and rigidity as compared with sliders formed by swaging and bending sheet material.

In the accompanying drawings, I have illustrated one desirable embodiment of the 15 present invention, by way of example, and have shown certain desirable steps in a preferred method of producing the improved slider, but wish it to be understood that the specific construction here illustrated and the 20 several steps and the order of steps here disclosed are by way of example only and are not to be regarded as limiting the scope of the invention.

In the drawings, 25 Fig. 1 is a fragmentary front elevation, to large scale, showing a fastener of the general type above referred to, provided with a slider constructed in accordance with the present invention;

30 Fig. 2 is a composite view showing in front elevation and in edge elevation, respectively, a blank of a desirable shape for use in constructing the improved slider;

35 Fig. 3 is a composite view showing in front elevation and in edge elevation, respectively, the appearance of the blank after it has been subjected to a suitable operation for producing a projection on its forward face adapted, at a later stage, to constitute a retainer for a 40 pull device;

Fig. 4 is an edge elevation of the blank at the end of the cutting operation which results in the formation of the front and rear wings of the slider;

45 Fig. 5 is a vertical section on the line 5—5 of Fig. 4;

Fig. 6 is a front elevation of a pull device of a type which may conveniently be assembled with the slider body herein disclosed;

50 Fig. 7 is an edge elevation of the complete slider, showing the inturned guide flanges at the edges of the front and rear wings and showing the pull device (in section) as attached to the retaining member on the front 55 wing;

Fig. 8 is a vertical section on the line 8—8 of Fig. 7;

Fig. 9 is a plan view of the slider shown in Fig. 7, but omitting the pull device;

60 Fig. 10 is a bottom plan view of the slider of Fig. 7, omitting the pull device;

Fig. 11 is a vertical section on the line 11—11 of Fig. 8;

Fig. 12 is a fragmentary edge elevation 65 similar to Fig. 4 but showing a modification;

Fig. 13 is a view similar to Fig. 12 but showing a further modification; and

Fig. 14 is a horizontal section on the line 14—14 of Fig. 13.

In Fig. 1 of the drawings the numerals 1 and 2 designate a pair of flexible stringers or tapes of the usual kind to whose opposed edges the series 3 and 4 respectively of fastener elements are secured. As here shown, these fastener elements are of the type more fully disclosed in the patent to Prentice and Legat No. 1,658,392 above referred to, but while this particular form of fastener is here illustrated, it is to be understood that the improved slider forming the immediate subject matter of the present application is applicable to other types of fastener as well as to that here specifically shown.

In the production of the improved slider, I first prepare a blank 6 from the material to be employed, (usually, although not necessarily metal) having roughly the outline and dimensions of the finished slider body. This blank may be cut, punched, or otherwise formed from the desired material.

As indicated in Fig. 2, the blank is of more or less keystone contour, comprising the top face 7, the bottom face 8, the lower lateral edge surfaces 9 and 10, and the upper edge surfaces 11 and 12.

In accordance with one desirable mode of procedure, this initial blank is made somewhat thicker in a front to rear direction than the desired slider body and is next subjected to pressure in suitable dies whereby it is somewhat thinned and expanded laterally and reduced substantially to the final external size and contour of the finished slider body.

At the same time, I prefer to form an integral projection on one face of the slider, preferably the front face, which later forms an anchorage for the pull device as hereafter described. In Fig. 3, I have shown the result of this shaping operation, it being noted that the lower face 8 of the blank has become longer than in Fig. 2 and that the edge faces 9 and 10 have taken an arcuate concave curvature.

In Fig. 3 the projection 13 formed in this operation is shown as extending from the top 7 to the bottom 8 of the slider body. While it is desirable to proceed as above described since the compression of the metal in thus shaping it adds to its density and homogeneity, I contemplate that if desired the original blank may be made of the proper thickness, lateral dimensions and contour to correspond to the finished slider body and that other means than the projection 13 might then be employed for attaching the pull device.

In whatever manner the final blank of Fig. 3 be formed, it is now subjected to a cutting operation whereby material from the interior of the blank is removed, leaving a slot 14 intermediate the front and rear portions 15 and 16 which now constitute the front and

rear wings of the slider. Preferably this slot 14 is produced by a milling operation which leaves the front and rear faces of the blank intact and which makes the opposed inner faces of the wings 15 and 16 smooth and accurately parallel. This slot 14 extends inwardly from the edges 9 and 10 and from the lower edge 8, but the cutting operation is so controlled as to leave an integral post or block 17 adjacent to the upper end of the slider body, such block forming a part of the original blank and being integrally united to both of the wings. Preferably the post or block 17, which will hereinafter be referred to as the "neck" of the slider, in accordance with terminology usually employed in this art, is of substantially triangular shape. As shown in Fig. 5 the upper face 7^a of this neck preferably coincides with the upper surface 7 of the blank, while the converging sides 18 and 19 of this neck member meet at a point 20 substantially below the surface 7^a and preferably about midway between the top and bottom surfaces 7 and 8 of the slider body. Preferably, the edge faces 18 and 19 of this neck member are concavely curved upon arcs more or less concentric with the curved edges 9 and 10 of the body. If the slot 14 be produced by a milling operation, these curved surfaces 18 and 19 may well represent the curvature of the edge of the milling cutter. These surfaces are smooth, uninterrupted, and without abrupt changes in shape, and are eminently well adapted to perform the function of guides for the opposed series of fastener elements.

In thus forming the slot 14 by a cutting operation, the metal of the slider body is not distorted or subjected to injurious stress, and the fiber of the metal in the neck portion 17 remains undisturbed and retains all of its original strength and ability to resist deformation. Referring to Fig. 11, it may be noted that the post or neck 17 is of homogeneous composition, wholly without folds, seams, sutures or the like, and thus throughout its entire depth possesses the inherent and original strength of the metal of the blank. This neck member 17, extending as it does downwardly from the upper surface of the slider body to a point substantially midway the length of the slider body, affords adequate resistance to separation of the front and rear wings, so that no external yoke or strengthening rib extending around the neck portion of the slider is necessary. The external dimensions of the slider body are thus kept at a minimum. The rear wing 16 at least of the slider body is wholly free from any projection, while the neck portion is also free of any projecting rib and is preferably flush with the upper surface of the slider body.

The next step in the operation preferably consists in bending the lateral edge portions

of one or both of the wings inwardly to form guide flanges 23 and 24. While I have here shown both the front and rear wings as provided with such guide flanges, I contemplate that when the slider is to be used with certain types of fastener element, it will not be necessary to provide lateral guide flanges upon but one of the wings.

Referring to Fig. 8, it may be noted that the depth of the neck 17 is such that it extends well below the upper ends of the lateral flanges 23 and 24, thereby forming clearly defined guide channels 25 and 26 of substantial length and uniform width at the upper end of the slider body, such channels merging into a single channel 27 at the lower part of the slider body. These channels are of accurate dimensions and have smooth and uniform defining walls and by reason of the substantial length of the upper channels 25 and 26 accurate, smooth, and easy interengagement of the opposed fastener elements is assured.

At some convenient point in the operation, either before or after the formation of the lateral flanges 23 and 24, I subject the projection 13 to a suitable operation or operations to adapt it for the reception of a pull device. As shown in Fig. 7 the projection has been pierced transversely to provide the elongate slot 28, leaving only the outer portion of the projection to form an elongate loop 13' integrally united at its upper and lower ends to the front wing of the slider body. To this loop I attach a suitable pull device which may, for example, be of the type shown in Fig. 6. This pull device comprises a piece of sheet material 29 cut to proper shape and having an opening 30 into which leads a slit 31 defining spaced pivot ears 32 and 33. In assembling the pull with the slider body the ears 32 and 33 may be sprung or bent apart sufficiently to enable them to be entered into the slot 28, whereupon they are returned to their original position, thus forming pivot elements for securing the pull to the loop 13'. In order to impart a pleasing appearance, the exposed surfaces of the slider may, if desired, be polished, plated, enameled, or otherwise finished appropriately to the use to which it is to be put.

The slider thus completed may be assembled with any desired form of fastener of the general type referred to and by reason of the accuracy of finish of its interior surface is found to operate much more smoothly and easily than any previously known form of slider. At the same time this improved slider is extremely rigid; it is very small; of minimum front to rear thickness; and of neat and pleasing appearance.

While the arrangement shown in Fig. 7 is desirable in providing an elongate loop 13', which permits the pull to be positioned either at the top or bottom of the slider, I con-

template that, as shown in Fig. 12, the loop 13^a may be of smaller dimensions, being located preferably at the central part of the front wing 15^a of the slider and having a 5 relatively small opening 28^a for the reception of the pivot elements of the pull.

In Figs. 13 and 14 I have shown a further modification in the production of which the original projection on the front face of the 10 wing is of the same length, as shown in Fig. 3, but wherein the projection is not perforated through its entire thickness, as shown in Fig. 7, but merely recessed at its opposite sides as shown at 28^b providing socket 15 slots for the pivot elements of the pull device, the outer member 13^b of the projection remaining of its original transverse thickness.

While I prefer to provide integral means 20 for attaching the pull device, as above described, I contemplate that the pull device may be secured by soldering or brazing directly or indirectly to the body of the slider at any desired point or may be attached in 25 any other manner familiar to those skilled in the art.

While I have herein illustrated and described a certain desired order of steps useful in producing my improved slider, I 30 wish it to be understood that this order of steps is not wholly essential but that the order may be varied and that it is within the scope of the invention to introduce other steps or, as above suggested, to omit certain 35 of the steps here disclosed without departing from the spirit of the invention. Neither is it essential that the external contour of the slider body or of the blank from which it is made be in exact accordance with the 40 present disclosure, or that the original blank be produced by cutting or punching from solid stock although this method is preferred. While metal is preferred in most instances as the material from which this slider is 45 made, I contemplate that other materials may be found useful for the purpose, and I regard the present method as applicable to the making of sliders from such other materials and wish it to be understood that the 50 claims appended hereto are not to be restricted by reference to the material employed.

I claim:

1. That method of making sliders for use 55 in separable fasteners of the class described which comprises as steps preparing a blank roughly approximating the desired slider in shape and size, and cutting away the material of the blank to leave spaced front and 60 rear wings having smooth inner surfaces and a substantially triangular neck integrally uniting the wings adjacent to one end, the neck having smoothly curved lateral surfaces converging toward the other end of the 65 slider.

2. That method of making sliders of the class described which comprises as steps preparing a blank, slotting the blank to provide front and rear wings integrally united at one end, and turning in the lateral margins 70 of one at least of the wings to provide guide flanges.

3. That method of making sliders of the class described which comprises as steps preparing a blank roughly approximating the 75 desired slider in shape and size, providing a projection on the front face of the blank, removing material from the interior of the blank to provide front and rear wings integrally united adjacent to one end, providing 80 the projection with a socket, and pivotally mounting a pull device in said socket.

4. That method of making sliders of the class described which comprises as steps preparing a blank roughly approximating the 85 desired slider in shape and size, forming a projection on its front face, removing material from the interior of the blank to provide front and rear wings integrally united adjacent to one end, shaping the material of 90 said projection to provide an elongate retainer integrally united to the front wing, and attaching a pull device to said retainer.

5. That method of making sliders of the class described which comprises as steps preparing a blank roughly approximating the 95 desired slider in shape and size, removing material from the interior of the blank to provide front and rear wings integrally united adjacent to one end, providing an 100 elongate loop integrally united at one end at least to the slider body, and attaching a pull device to said loop.

Signed by me at Berlin, Connecticut, this 105 twenty-sixth day of June 1928.

GEORGE E. PRENTICE.
